Patented Apr. 25, 1922.

FIG. 1.

FIG. 2.

FIG. 3.

FIG. 4.

FIG. 5.

Inventor.
Chester W. Brown

UNITED STATES PATENT OFFICE.

CHESTER W. BROWN, OF CHICAGO, ILLINOIS.

KNIFE AND SCISSORS SHARPENER.

1,414,172.

Specification of Letters Patent. Patented Apr. 25, 1922.

Application filed November 13, 1919. Serial No. 337,897.

To all whom it may concern:

Be it known that I, CHESTER W. BROWN, a citizen of the United States, residing at the city of Chicago, in the county of Cook and State of Illinois, have invented certain new and useful Improvements in Knife and Scissors Sharpeners, of which the following is a specification.

My invention relates to sharpening devices for knives, scissors, and the like, in which rotary abrasive wheels are employed and is usable on all edged tools requiring sharpening on one side or on both sides.

One object of my invention is to provide a rotary sharpening device wherein the operation of moving the blade to be sharpened backward and forward in contact with the wheels, causes the wheels to rotate, and grind the edge of the knife or blade.

Another object is to provide a sharpening device wherein one element is beveled to sharpen the beveled side of edged tools, and the other element is flat, to sharpen the flat side of the same tool.

Another object is to provide adjacent the sharpening element means for guiding and sharpening scissors and shears on the same device.

With the foregoing and other objects in view, my invention consists in the arrangement and combination of parts hereinafter described and claimed, and while the invention is not restricted to the exact details of the construction disclosed, still, for the purpose of illustrating a particular embodiment thereof, reference is had to the accompanying drawings in which like reference characters designate the same parts in the several views and in which,

Figure 1 is a section view showing the cross section and relative position of the different elements, and knife blade.

Figure 2 is a side elevation, showing the blade of a shear in the shear sharpening guide.

Figure 3 is an end view of the sharpener, showing it in use in sharpening a blade beveled on one side.

Figure 4 shows a variation in which the shear guide is at the side of the handle.

Figure 5 shows another variation in which one portion of the shear guide is omitted.

Referring now more particularly to the drawings, I have shown my sharpening device as composed of the two abrasive wheels

1 and 2, rotatably mounted upon a shaft as 3. For convenience in use and operation, the shaft 3 I have mounted in a convenient handle, as the flat wire U shaped handle 4 shown. I have preferably made the wheel 1 in the 65 shape of a truncated cone, with the angle to suit the angle of the tool to be sharpened as 5. The wheel 2 I have preferably made flat on one side, and on the side adjacent to wheel 1, I have made it with a narrow rim 65 preferably flat, with the middle portion concave, to form a complement to the wheel 1.

For the purpose of holding the wheels 1 and 2 against the blade inserted between them in sharpening, I provide the spring 6 70 mounted upon the shaft between one of the wheels and the side of the handle. For convenience in assembling I have made the shaft 3 with a bolt head as at 7, and threaded at its reverse end 8. On this shaft I have provided a thumb or wing nut 9 for readily adjusting the tension of the spring 6 against said wheels, and I have also provided a lock nut as 10 for holding said parts in operating position when suitably adjusted and against 80 accidental movement.

Mounted upon the shaft adjacent to one limb of the handle I have provided the guide 11 for guiding scissor and shear blades as 85 they are being sharpened on the flat side of wheel 2. This guide consists of the portion 12, with the hole therein for reception of the shaft 3. One end is bent up slightly to form a bearing on the edge of the handle, while the other and longer end is formed into a U 90 shaped loop 13, and the scissor or shear blade is inserted between the limbs of said U shape in sharpening, as shown in Figure 2. At Figure 1 I have shown this guide as disposed within a bend of the limb of the handle, and in Figure 4 the scissor and shear blade guide 11^a is arranged at an angle to the position shown in Figure 1, and it has its portion 12^a disposed transversely of one side of the handle and its loop 13^a projecting from the handle, while in Figure 5 I have shown the guide 11^b as composed of only one limb 12^b, the shear blade being held disposed thereagainst in sharpening. 95

In sharpening the blades of butcher, 105 kitchen, and other moderately sized knives, which can be inserted between the limbs of the handle, the blade is placed between the wheels as shown in Figure 1, and pushed backward and forward. As the blade moves 110

backward and forward the friction against the wheels causes them to revolve, and they grind the edge of the blade to the desired sharpness. In knives which are sharpened on both sides, it is best to reverse the sharpener, and employ the beveled wheel on both edges, as a better result is obtained. When it is desired to sharpen larger tools, like the knives of paper cutters and the like, and those with a bevel on only one side, the device is placed upon the edge of the blade as shown in Figure 3 with wheel 1 on the side having the bevel, and wheel 2 on the side not beveled, and the sharpener is moved backward and forward lengthwise of the blade, and in this movement the friction of the knife against the wheels causes them to rotate, and thus grind the edge to the required sharpness. It will also be understood, that more or less pressure may be employed in applying the sharpener to the blade, and that the spring tension may be adjusted to any variation of work required.

In sharpening shears, scissors, and the like, the blade to be sharpened is inserted between the limbs of the guide 13 as shown in Figures 2 and 4, with the edge in proximity to wheel 2, and the blade is moved backward and forward lengthwise of the blade, being held firmly against the flat surface of wheel 2 and thereby the edge is ground to the desired shearing angle and sharpness. When using the variation shown in Figure 5, the inside flat side of the shear blade is held against the guide to merely secure the proper angle in sharpening, and the blade is moved forward and backward as above described. The advantage of this variation, is that it accommo-

dates all sizes no matter how large or small 40 the blade may be.

Having thus described my invention, what I claim and desire to secure by Letters Patent, is the following:

1. In a sharpener for knives, scissors, 45 shears and the like, the combination of a handle, a grinding wheel mounted on said handle and having a flat surface, and a substantially U-shaped guide carried by the handle and opening adjacent the said flat 50 surface and extending in an outward direction from the same near the perpendicular to the said flat face of the grinding wheel for guiding the blades of scissors or shears as they are being sharpened upon said flat 55 surface of said wheel.

2. In a sharpener for knives, scissors, 60 shears and the like, the combination of a handle, two grinding wheels mounted upon said handle, a guide for scissors and shears 65 blades separate from and supported by the handle mounted adjacent one of said wheels, said guide having a member disposed parallel the flat surface of said wheel, and a second member extending in an outward direction near the perpendicular to said flat surface of said wheel, for guiding the blades of scissors or shears as they are being sharpened upon said flat surface of said wheel, substantially as shown and described. 70

In testimony whereof, I have hereunto set my hand, in the presence of two witnesses, at the city of Chicago, State of Illinois, this 31st day of July, 1919.

CHESTER W. BROWN.

Witnesses:

HENRY J. HALVERSON,
M. J. PADDON.
